UNITED STATES PATENT OFFICE.

ROBERT S. GRAHAM, OF NEW YORK, N. Y., ASSIGNEE OF ONE-HALF TO WILLIS H. FOLLMER, OF NEW YORK, N. Y.

REMOVABLE CAP FOR TYPEWRITER KEYS.

Application filed February 4, 1922. Serial No. 524,013.

To all whom it may concern:

Be it known that I, ROBERT S. GRAHAM, residing in the city, county, and State of New York, have invented certain new and useful Improvements in a Removable Cap for Typewriter Keys, of which the following is a full, clear, and exact description, such as will enable others skilled in the art to which it appertains to make and use the same.

This invention relates to a removable cap for typewriter keys and the objects of the invention are to provide a removable cap that is interchangeable without reference to the index letter or numeral of the typewriter key to which it is to be applied.

To the accomplishment of the above objects and to such others as may hereinafter appear the invention comprises a removable cap having a top opening made of elastic material which is arranged to interchangeably fit a plurality of typewriter keys.

Referring to the drawings:

Figure 1 is a perspective view of the key end of a typewriter key bar provided with a removable cap made in accordance with the invention.

Figure 2 is a top view of Fig. 1.

Figure 3 is a sectional view on the line 3—3 of Fig. 2.

Figure 4 is a sectional view on the line 4—4 of Fig. 2.

Figure 5 is a bottom view of Fig. 1 the key bar being shown in section.

In the drawing A designates the key end of an ordinary typewriter key bar which is provided in the present instance with the usual typewriter key comprising, a circular disk B having on its upper surface an index letter or numeral, the same being covered with a circular disk C of glass, both supported on a metal key base D having an upturned edge E and a shank F secured to the upturned portion of the key bar. The disks B and C are held in position on the top of the key base D by means of a circular flange G surrounding the outer edge of the upturned edge E and crimped over the top thereof and the circumferential edges of the disks B and C.

The typewriter key above described is similar to the typewriter keys in use on a great variety of typewriters and is adapted to be covered by a removable resilient rubber

cap H made in accordance with the present invention.

The typewriter key cap H is preferably made of rubber suitably molded to provide a hollow disk shaped cap which is provided with a base a having an opening b which permits of the cap being stretched over the circumferential edge of the circular flange G to tightly engage the typewriter key as shown in the drawings.

The key cap H is, in accordance with the present invention, provided with a top opening so as to make visible the index letter or numeral on the disk B. In the present instance the top opening in the key cap H is made greater in length than in breadth the greater length being in the direction of the key bar to more easily show the index letter or numeral, although if desired the top opening can be made round or other convenient shape to expose the index letter or numeral.

To securely hold the key cap H in position and also to provide a resilient working surface for the fingers of the operator the same is provided with comparatively thick side cushion members c on the circumference of the top opening, as shown in Fig. 3 which preferably do not extend all the way around the circumference but terminate in end cushion members d as shown in Fig. 4. The side cushion members c and end cushion members d are preferably formed in the shape of a downwardly extending lip so as to securely engage the crimped end of the circular flange G. The end cushion members d are also preferably in line with the base opening b so as to facilitate the cap being readily stretched over the key, the end cushion member d being comparatively thin facilitating this operation.

From the above description it will be seen that a resilient typewriter key cap is provided that is interchangeable, due to the fact that the same is provided with a top opening through which the index letter or numeral can be seen, which makes it possible to interchange the caps from one typewriter key to another or replace the same at will without reference to key index letter or numeral. The interchangeable feature of the cap is important for the reason that if one wears out or breaks it can easily be replaced with another without reference to the index letter or numeral as will be readily understood.

It will also be seen that a cap made as above described will cushion the fingers of the operator and will effectively prevent slipping of the fingers.

5 While the invention has been described with particular reference to the details of construction the same is not to be considered as limited thereto as many changes can be made and still fall within the scope of the 10 invention set forth in the following claims.

What I claim is:

1. A cap for a typewriter key arranged to be removably secured thereto, the top of said cap being provided with side and end 15 cushion members, said side members being broader than said end members, and an opening in the top of said cap surrounded by said cushion members.

2. A cap for a typewriter key made in the 20 form of a hollow disk having a bottom member provided with an opening to permit of the same being stretched over a typewriter

key, the top of said cap being provided with side and end cushion members, said side members being broader than said end members, and an opening in the top of said cap surrounded by said cushion members. 25

3. A cap for a typewriter key made in the form of a hollow disk having a bottom member provided with an opening to permit of 30 the same being stretched over a typewriter key, the top of said cap being provided with side and end cushion members having a downwardly extending lip said side members being broader than said end members, 35 and an opening in the top of said cap surrounded by said cushion members.

In testimony whereof I have signed this specification in the presence of two subscribing witnesses.

ROBERT S. GRAHAM.
